(57) **CLAIM**

The ornamental design for a cell phone grip, as shown and described.

DESCRIPTION

FIG. 1 is a perspective view of the cell phone grip, showing the new design;

FIG. 2 is a top plan view of the cell phone grip thereof;

FIG. 3 is a front elevational view of the cell phone grip thereof;

FIG. 4 is a right side elevational view of the cell phone grip thereof; and,

FIG. 5 is a rear elevational view of the cell phone grip thereof.

The bottom plan view of the cell phone grip is a mirror image of the top plan view of the cell phone grip shown in FIG. 2.

The left side elevational view of the cell phone grip is a mirror image of the right side elevational view of the cell phone grip shown in FIG. 4.

The broken lines in the drawings illustrate environmental subject matter and form no part of the claimed design.

1 Claim, 3 Drawing Sheets
